UNITED STATES PATENT OFFICE

2,077,200

FREEZING TRAY

Leonard W. Atchison, Schenectady, N. Y.; assignor to General Electric Company, a corporation of New York

Application March 1, 1935, Serial No. 8,872

4 Claims. (Cl. 62—108.5)

My invention relates to freezing trays for refrigerating machines, and more particularly to partition assemblies for such trays.

It is an object of my invention to provide an improved partition assembly for freezing trays in which the length of the partition assembly may be readily varied during assembly to accommodate freezing trays of different lengths, which is economical to manufacture and which is of strong and rugged construction. I accomplish this by utilizing a plurality of partition elements which are preferably punched, or otherwise formed, from sheet material, each partition element having a longitudinally extending portion and oppositely extending lateral portions arranged at each end of said longitudinal portion. The individual partition elements, so formed, are rigidly secured together to form a partition assembly.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is a perspective view of a freezing tray containing a partition assembly embodying my invention; and Fig. 2 is a perspective view of the partition assembly shown in Fig. 1 and of a block of ice removed therefrom.

Referring to the drawing, in Fig. 1 I have shown a shallow rectangular metal freezing tray 10, containing a partition assembly. This partition assembly is made of a series of duplicate partition elements which are spot welded, or otherwise rigidly secured, together, at the adjacent surfaces thereof.

The provision of a freezing tray assembly made up of a series of partition elements having angularly disposed portions and secured together at their abutting surfaces is not my invention, but is the invention of Frank Conway and is described and claimed in his application Serial No. 8,867, filed March 1, 1935, and assigned to the General Electric Company, the assignee of my present invention.

Each of the duplicate partition elements 11, which are preferably made of aluminum or other flexible material, are provided with a longitudinally extended central portion 12 and oppositely extending transverse portions 13 and 14 at each end, respectively, of the longitudinally extending portion. The partition elements 11

are thus of a substantially Z-shaped cross-section. The partition elements 11 are assembled in series relation with the central portions 12 thereof in substantial axial alinement along the center of the partition assembly, a part of the central portion of each partition element overlapping a part of the central portion of the next successive partition element in the assembly. These overlapping parts of the central portions 12 of the partition elements are rigidly secured together preferably by the fusion of metal, that is, by spot welding, soldering, or the like, thus forming joints of good thermal conductivity therebetween. The distance by which one or more of the partition elements overlap the adjacent partition elements may be varied during manufacture before they are secured together. In this way, the total length of the partition assembly may be varied in order that the finished assembly will fit snugly into a freezing tray of any predetermined length. The transverse portions 13 and 14 of the partition elements 11 are disposed in spaced parallel relation with respect to each other, thus dividing the tray 10 into a series of individual compartments in which blocks of ice, or the like, may be frozen. The lower corners of the transverse portions 13 and 14 of the partition elements 11 are rounded in order to conform closely to the bottom of the tray 10, which is provided with rounded edges as illustrated.

An L-shaped end partition element 15 is rigidly secured to one end of the partition assembly, described above. The end partition element 15 includes a longitudinally extending portion 16 and a transversely extending portion 17. The end partition element 15 is preferably secured to the adjacent Z-shaped partition element 11 by the fusion of metal as, for example, by spot welding the part of the longitudinal portion 16 of the end partition element 15 adjacent the edge thereof to the abutting part of the longitudinal portion 12 of the partition element 11. A second end partition element 18 is secured to the opposite end of the partition assembly in the same manner, as that described, with respect to the end partition element 15.

The partition elements which constitute the partition assembly, described above, are preferably made of resilient sheet material, such as aluminum, in order that the longitudinal portion of the resulting structure may be readily flexed manually or otherwise in a lateral direction to the position shown in Fig. 2. In removing blocks of ice, or the like, from the freezing tray 10, the tray may be warmed by apply-

ing warm water to the bottom thereof. When the freezing tray 10 is warmed, in this manner, the cubes of ice, or the like, will be melted along the exterior sides thereof causing a breakage of 5 the bond between the blocks of ice and the freezing tray, so that the partition assembly and the blocks of ice contained therein may be readily removed from the freezing tray 10. After the 10 partition assembly and the ice contained therein have been removed, in this manner, the removal of the individual blocks of ice from the partition assembly is facilitated by the flexibility of the partition assembly. The blocks of ice are 15 first removed from one side of the partition assembly then the longitudinal portion of the partition assembly is bent outwardly, and as a consequence the transversely extending portions 14 of the adjacent partition elements 11 are spread apart, thus breaking the bond between their inner surfaces and the remaining blocks of ice 20 therein such as the block of ice 19, so that the remaining blocks of ice are allowed to fall freely therefrom, as shown in the drawing.

It will thus be seen that I have provided a 25 partition assembly for a freezing tray which provides a series of ice cube compartments which may be economically manufactured by punching, or otherwise forming, a large number of duplicate partition elements from sheet material.

The length of the partition assembly may be 30 varied during the manufacture thereof by varying the amount by which one partition element overlaps the adjacent partition element and also by varying the number of partition elements employed, so that freezing trays of various lengths 35 may be readily fitted. When these partition elements are secured together in the manner, described above, they form a strong rugged structure which will withstand hard usage.

40 While I have shown a particular embodiment of my invention in connection with a rigid metallic freezing tray, I do not desire my invention to be limited to the particular construction shown and described, and I intend, in the appended claims, to cover all modifications within the spirit and scope of my invention.

What I claim as new and desire to secure by Letters Patent in the United States is:

1. In combination with a freezing tray, a 45 removable partition assembly comprising a plurality of similar flexible metallic partition elements, each of said partition elements having a

longitudinally extending portion and oppositely extending transverse portions at each end of said longitudinally extending portion, said partition elements being arranged in series with a part of the surface of said longitudinal portion of each of said partition elements in abutting relation with said part of the surface of the longitudinal portion of another of said partition element, said abutting surfaces of said partition elements being rigidly secured together. 5

2. In combination with a freezing tray, a removable partition assembly comprising a plurality of similar flexible metallic partition elements, each of said partition elements having a longitudinally extending portion and oppositely extending transverse portions at each end of said longitudinally extending portion, said partition elements being arranged in series with a part of the surface of said longitudinal portion of each of said partition elements in abutting relation 10 with said part of the surface of the longitudinal portion of another of said partition element, and means including fused metal for securing 15 said abutting surfaces of said partition elements together. 20

3. In combination with a freezing tray, a removable partition assembly comprising a plurality of substantially Z-shaped flexible metallic partition elements, said partition elements being arranged in series with a part of the surface of the central portion of each of said partition elements overlapping a part of the surface of the central portion of another of said partition elements in abutting relation therewith, said abutting 25 surfaces being secured together, the legs 30 of said partition elements being arranged in spaced parallel relationship. 35

4. In combination with a freezing tray, a removable partition assembly comprising a plurality of duplicate substantially Z-shaped flexible metallic partition elements, said partition elements being arranged in series with a part of the surface of the central portion of each of said partition elements overlapping a part of the surface of the central portion of another of said partition elements in abutting relation therewith, and means including fused metal for securing 40 said abutting surfaces together, the legs of said partition elements being arranged in spaced parallel relationship. 45
